UNITED STATES PATENT OFFICE.

ANTONIO LONGORIA, OF CLEVELAND, OHIO, ASSIGNOR TO THE STERLING CORPORATION COMPANY, OF CLEVELAND, OHIO, A CORPORATION OF OHIO.

ELECTRIC WATER-HEATER.

1,288,069.

Specification of Letters Patent.

Patented Dec. 17, 1918.

Application filed February 21, 1916. Serial No. 79,623.

To all whom it may concern:

Be it known that I, ANTONIO LONGORIA, subject of the King of Spain, residing at Cleveland, in the county of Cuyahoga and State of Ohio, have invented certain new and useful Improvements in Electric Water-Heaters, of which the following is a specification.

This invention relates to improvements in heaters and particularly to electric water heaters.

More specifically the invention relates to an electric water heater comprising a casing connected on the inlet side to the water supply and of a type such that a plurality of heating elements may be supplied between the end plates so as to increase or decrease the capacity of the heater. The invention also relates to the location of a suitable controlling valve and switch mechanism on the inlet and to other details such as the construction of the units themselves and the electric connections.

The invention may be further briefly summarized as consisting in the construction and combination of parts hereinafter set forth in the following description, drawings and claims.

Referring to the drawings Figure 1 is a side elevation of the device; Fig. 2 is a vertical section taken through the center from front to rear, but showing portions of the elements with one of the heating units broken away to a point where it will show the electrical connections leading from the element to the outside; Fig. 3 is a view in section through the blade of the switch showing the electrical connections; Fig. 4 is a front elevation with parts broken away; Fig. 5 is a sectional view through one heating element; Fig. 6 is a detailed view showing the connection between the valve plug and the switch member.

In the embodiment shown in the drawings 1 represents the front plate which is provided with a suitable spout 2 and an inwardly extending flange 3 about its periphery, the flange being spaced from the lower end of the plate and forming an extension 4 beyond the flange for a purpose to be described. The casing also comprises a back plate 5 having an inwardly extending flange 6 and an extension 7 corresponding to the extension 4. This plate is provided with an opening 8 communicating with a boss 9 re-

ceiving a pipe connection 10 leading to a valve member 11 provided with a valve plug 12 having an operating wheel 13 extending to one side of the heater casing as shown in Fig. 4. This valve member is connected to a suitable pipe 14 leading to any source of water supply. The valve structure is similar to any other valve cock and has an opening 15 for permitting the water to pass to the heater. The flange 6 of the back casing plate 5 is provided with an upwardly extending flange 16 in front of the opening 8 and preventing the impinging of the water against the heating element as will appear.

The front and back casing plates 1 and 5 are connected by suitable screws or through bolts 17 properly spaced around the casing and it is between these plates and upon these screws that the several heating units are arranged.

In the drawings there are three heating units shown, the two outer ones being similar in structure and the inner one being similar in all respects to the other two except for the electrical connection and a description of one and a detailed description of the electrical connection of the center one will suffice for all. Each of the heating units comprises a pair of copper plates 18 corresponding in size to the flanges 3 and 6 spaced by fiber or other similar frames 19 which are arranged side by side and these frames form an inner heating element chamber 20. These frames at the sides correspond in width to the flanges 3 and 6, but at the upper and lower ends are wider and they together with the copper plates are provided with openings for receiving eyelets 21 which are provided with flanges 22 at each end serving to clamp the parts together, the eyelets forming a means of communication from one side of the unit to the other. The eyelets are preferably provided in one end of each plate, as shown, or in both ends depending upon whether a series or a parallel circulation of water is to be utilized through the heater. If the water is to circulate in parallel through the heater then the eyelets are provided at the top and bottom. The fiber frames 19 at the lower end of the casing are provided with recesses 23 which form openings for the conductor strips leading from the elements as will appear.

Each of the heating elements comprises a plate 24 of a heat conducting insulating

composition with a wire 25 embedded therein to serve as the heating element itself, and this wire is preferably arranged in the plate as shown at 25, with one end secured to a 5 ribbon conductor 26 and the other end secured to a ribbon conductor 27. These ribbon conductors pass out through the openings formed by the recesses 23 in the fiber frames. In the arrangement shown there are 10 three heating units and these units are spaced by means of frames 28 which correspond in size and shape to the flanges 3 and 6. The front and back plates together with the several heating elements are all held tightly together by the screws 17.

In the arrangement shown an eyelet 21 is provided in the upper end of each of the two outside units and in the lower end of the central unit so that the water entering 20 through the opening 8 engages the flange 16 and passes up through the chamber formed between the right hand element and the plate 5 to the eyelet 21 at the top. From this it passes to the next water chamber formed by 25 the frame 28 down to the eyelet 21 at the lower end of the central unit, then upward on the other side of this unit to the eyelet of the left hand unit and from thence down to the discharge opening leading through 30 the front plate. In this way a circuitous or series course is provided for the water so that it engages all of the units in the heater.

Secured to the extension 4 of the front casing plate is a fiber block 29 held in place 35 by suitable screws 30. This fiber block receives two binding screws 31 having threaded shanks 32 extending through the block and within the heater casing for the reception of the flat wire connections 26 and 40 27. These binding screws also serve to receive the incoming wires, nuts 33 being provided for holding the connections. The space between the extensions 4 and 7 is 45 closed by a cover 34 which is U-shaped in cross section as shown in full and dotted lines in Fig. 4.

The hand wheel 13 is provided with suitable indications or legends such as "Hot", "Off", "Cold", "Off" and these legends are 50 utilized in connection with the index point 35 secured to the casing. Any suitable type of snap switch may be employed so long as there is some connection with the valve plug and I have shown in Fig. 3 the arrangement of the switch members of an ordinary snap switch type showing how the current of the heating elements is controlled and in this view 36 represents the base or body portion of the switch which is mounted upon a 55 bracket 37 secured to the casing in any convenient manner. Mounted on this base, which is porcelain or some insulating material, are suitable stationary contact blades 38 of a well known type each having a suitable binding screw 39 for connection in the

circuit. At an angle of 90° to this member 38 is a similar member 40 having a binding screw 41. Mounted at the center is an actuating shaft 42 which is square and receives an insulating bushing 43 arranged inside of the switch member 44. This switch member 44 has blades 45 which are adapted to coöperate with the contact members 38 and 40 in a well known manner. In the position in which the parts are shown in 70 Fig. 3 the current is supplied to the heating elements and assuming that water is being supplied to the heater then it will be heated by the elements. If the operator wishes to close the valve, he turns the wheel 13 in a 80 clockwise direction as shown in Fig. 1 until the word "Off" appears opposite the index point 35. This causes the switch member 44 to assume a position at 90° to that shown in Fig. 3 when the circuit will be broken. 85 The next 90° turn of the wheel will bring the word "Cold" to the index point when cold water will pass through the device, the switch member being out of engagement entirely with the contacts.

90 The connection between the switch actuating shaft 42 and the valve plug consists of a hollow square socket 46 formed in the shaft and adapted to receive the squared shaft 47 formed on the end of the valve 95 plug 12.

Having described my invention, I claim:—

1. An electric water heater, comprising a casing having water passages therein, a valve controlling the flow of water through said passages, said valve having two different open positions, an electric heating element arranged to heat the water flowing through said passages, an electric circuit therefor, and a switch controlling said circuit, said switch having open and closed positions and being so connected to said valve that in one of said valve positions the switch is open and in the other of said valve positions the switch is closed.

110 2. An electric water heater, comprising a casing having water passages therein, a valve controlling the flow of water through said passages, said valve having two open positions and a closed position, an electric heating element adapted to heat the water flowing through said passages, an electric circuit for said element, and a switch controlling said circuit, said circuit having a closed and two open positions and being so connected to said valve that in one of said open valve positions the switch is closed and in said other open valve position the switch is open.

115 3. An electric water heater, comprising a casing having water passages therein, a rotating valve controlling the flow of water through said passages, said valve having two opposite open and two opposite closed positions located ninety degrees apart, an 120

125 130

electric heating element adapted to heat the water flowing through said passages, an electric circuit for said element, and a rotatable switch controlling said circuit, 5 said switch having four positions at ninety degrees apart and closing said circuit in one only of said positions, said switch being connected to rotate with said valve and being so arranged as to close said circuit in 10 one only of the open positions of said valve.

4. In an electric water heater a front plate, a spacing frame member upon the back thereof, a water connection for the front plate, a rear plate, an inwardly extending spacing frame extending therefrom, a water connection for the rear plate, a heating element arranged between the said 15 spacing frame members and having a passage therethrough for conducting fluid therethrough, and means in front of the inlet 20 in the rear plate for preventing the incom-

ing stream of fluid from impinging against the element.

5. In an electric water heater a front plate, a spacing frame member upon the 25 back thereof, a water connection for the front plate, a rear plate, an inwardly extending spacing frame extending therefrom, a water connection for the rear plate, a heating element arranged between the said 30 spacing frame members and having a passage therethrough for conducting fluid therethrough, and a baffle in front of the inlet for preventing the incoming stream of fluid from impinging against the element. 35

In testimony whereof I affix my signature in presence of two witnesses as follows.

ANTONIO LONGORIA.

Correction in Letters Patent No. 1,288,069.

It is hereby certified that Letters Patent No. 1,288,069, granted December 17, 1918, upon the application of Antonio Longoria, of Cleveland, Ohio, for an improvement in "Electric Water-Heaters," were erroneously issued to The Sterling Corporation Company, assignee, whereas said Letters Patent should have been issued to *The Sterling Electrical Corporation Company, assignee, by mesne assignments*, as shown by the records of assignments in this office; and that the said Letters Patent should be read with this correction therein that the same may conform to the record of the case in the Patent Office.

Signed and sealed this 1st day of April, A. D., 1919.

[SEAL.]

R. F. WHITEHEAD,
Acting Commissioner of Patents.
